(57) **CLAIM**

The ornamental design for a surface sanitizer, as shown and described.

DESCRIPTION

FIG. 1 is a front view of a surface sanitizer showing my new design;

FIG. 2 is a bottom view thereof;

FIG. 3 is a top view thereof;

FIG. 4 is a first side view thereof; and,

FIG. 5 is a second side view thereof.

The broken line showing of a standoff in FIGS. 1 and 3 is for the purpose of illustrating environmental structure and form no part of the claimed design. The broken line showing of a surface sanitizer in FIGS. 4 and 5 is for the purpose of illustrating portions of the article that form no part of the claimed design.

1 Claim, 5 Drawing Sheets
